BOMB

Russell T. Robertson, New Windsor, Md.

Application September 16, 1942, Serial No. 458,534

1 Claim. (Cl. 102—2)

My invention relates to improvements in aerial bombs of the fragmentation type, the principal object in view being to equip such devices inexpensively for exploding above the target, or the ground, as the case may be, to provide for scattering of the fragments over a maximum area.

To the accomplishment of the above, and subordinate objects presently appearing, a preferred embodiment of my invention has been illustrated in the accompanying drawing, set forth in detail in the succeeding description, and defined in the claim appended hereto.

In said drawing:

Figure 1 is a view in side elevation of a bomb equipped according to my invention,

Figure 2 is a similar view partly broken away and shown in section, and

Figure 3 is a view in section of the nose section of the bomb and parts carried thereby.

Referring to the drawing by numerals, my improved bomb, as shown, comprises an oval, streamlined, hollow body 1 forming therein a chamber 2 for the explosive charge 3 and embodying a separate detachable nose section 4, and suitable tail fins 5 for stabilizing the bomb in flight.

The nose section 4 is attached by means of a reduced externally threaded rear end shank 5 thereon turned into a suitable socket 6 in said body 1 communicating with the front end of the chamber 2. An axial through bore 7 is provided in the nose section 4 for a purpose presently seen. A cap anchoring plate 8 is clamped in the rear end of the socket 6 by the shank 5 and which has suitably secured therein a firing cap 9 aligned with the inner end of the bore 7.

Extending axially from the nose section 4 for a substantial distance is an elongated firing rod 10 having an inner end portion slidably fitted in the bore 7 and provided with a reduced part 11 terminating in a head 12, said part 11 providing a notch 13 in said rod 10 in advance of the head 12. The outer end of the rod 10 is equipped with a flared foot 14 for impact with a target or the ground, as the case may be. A coil spring 15 surrounding the rod 10 between the nose section 4 and a cross pin 16 extended through the rod urges the latter outwardly of the nose section 4.

The firing rod 10 is limited as to outward movement thereof by means of a detent plug 17

slidably mounted in the reduced inner end of a radial bore 18 provided in the nose section 4, the detent plug being backed by a spring 19 retained in said bore 18 by a screw plug 20. The 5 detent plug 17 normally fits in the notch 13 with the head 12 of the firing rod bearing against one side thereof.

The operation of the described bomb will be readily understood. As the firing rod contacts 10 the target, or the ground, it is moved inwardly of the nose section 4 so that the head 12 impacts the cap 9 and the latter ignites the explosive charge 3, the spring 15 and pin 16 limiting inward movement of the firing rod so that the 15 body 1 is exploded remote from the target or other object against which the foot 14 of said rod 10 strikes.

It will be noted that the nose section 4, firing rod 10, spring 15 and parts carried by the nose 20 section may be detached as a unit for charging the bomb or for use, if not damaged, for replacement purposes.

The foregoing will, it is believed, suffice to impart a clear understanding of my invention without further explanation.

Manifestly, the invention, as described, is susceptible of modification without departing from the inventive concept, and right is herein reserved to such modifications as fall within the scope of the subjoined claim.

30 What I claim is:

A bomb of the class described comprising a hollow body forming a charge containing chamber therein, and a detachable nose section axially bored, a firing cap in said body at the inner end of said bore, an elongated firing rod extending forwardly from said nose section and having an inner end slidably mounted in said bore for movement inwardly of the bore under impact against a target to fire said cap, coaxial devices in said nose section and on said rod for yieldingly blocking such inward movement of said rod and limiting outward movement thereof, and spring means urging said rod outwardly of 35 said section, said devices comprising a spring 40 pressed detent plug in said nose section and a notch in said rod with which said plug is interlocked, said notch being constructed and arranged to cam the plug out of the same under 45 inward movement of said rod.

FUEL COMPOSITION

Louis A. Mikeska, Westfield, and John C. Zimmer
and Jones I. Wasson, Union, N. J., assignors to
Standard Oil Development Company, a corpora-
tion of Delaware

No Drawing. Application November 26, 1940.
Serial No. 367,230

25 Claims. (Cl. 44—62)

This invention has to do particularly with protecting hydrocarbon motor fuel compositions from objectionable influences of corrosive impurities and sunlight by the addition of small but effective quantities of organic compounds characterized by ammonium derivatives of alkyl phenol-formaldehyde-hydrogen halide condensation products.

Liquid hydrocarbon fuels employed in internal combustion engines and burners, even though highly refined, are apt to be contaminated with some corrosive impurities such as sulfur- or oxygen-containing compounds, which give rise to a number of difficulties. These impurities are nuisance factors in the corrosion of metal containers, fuel supply lines and engine parts; they lead to bad engine conditions, to lowering of anti-knock value in a spark ignition engine motor fuel and to certain forms of deterioration in the appearance of the fuel.

The undesirable changes in motor fuel compositions arise from a number of different causes, and it is difficult to correct for the effects of all causes by any single stabilizing agent. For example, antioxidants have been used to increase the resistance of a fuel to oxidation, which causes change of color and formation of gum. But this correction by itself is not always sufficient, for it has been found that low boiling hydrocarbon liquids free from gum-forming bodies are subject to discoloration by sunlight and even many of the well-known antioxidants become discolored by sunlight and tend to make the oil cloudy.

Another form of undesirable change occurring particularly in spark ignition motor fuels is due to the instability of metallo-organic anti-knock addition agents, as for example, lead alkyl anti-knock agents, for these compounds have a tendency to decompose and form a precipitate in the fuel, especially when exposed to sunlight or when stored in contact with various metals commonly used in fuel containers.

Still another type of deterioration encountered with hydrocarbon fuel distillates is their discoloration by the action of metals, which action is accentuated when the oils are at elevated temperatures.

An object of the present invention is to provide fuel compositions in which the undesirable effects of corrosive impurities and sunlight are satisfactorily suppressed.

A more specific object is to preserve the clarity and stability of motor fuels containing metallo-organic anti-knock agents with improvement and preservation of the effectiveness of these agents. A further specific object is to confer on the fuel distillates an inertness to metals so as to prevent discoloration or contamination of the fuel, the surface of the metal contacted by the fuel

being made passive at the same time to corrosion by impurities in the fuel.

The type of agent utilized for the purpose of this invention is characterized by ammonium derivatives of alkyl phenol-formaldehyde-hydrogen halide condensation products. These compounds are obtained with satisfactory oil-solubility and effectiveness for the objects of this invention by condensing an alkyl phenol with formaldehyde 10 in the presence of a hydrogen halide acid, then reacting the resulting phenolic condensation product with liquid ammonia or an equivalent strong base, e. g., an amino compound, an organic nitrogen base, or other organic bases, 15 which may contain other metalloids, such as phosphorus. Liquid ammonia is the highly preferred base reactant. Next in order of importance come the aliphatic amines and aromatic amines, primary, secondary, and tertiary.

20 A very important factor in the preparation and use of these agents is that their effectiveness and oil-solubility increases with the length of the alkyl substituent in the phenol nucleus.

Even though the initial phenolic compound 25 contains a long alkyl or aliphatic substituent group, which in ordinary types of reaction lowers the reactivity of the phenolic compounds, the reaction for preparing the desired agent goes with great ease. The complete reaction may be considered as involving two stages: first, a substitution 30 of a halogenated aliphatic radical in the phenolic compound; and second, a splitting out of the halogen by condensation of the substituted phenolic compound with the base. Very little halogen, and preferably none, is left in the final product. The preparation of the preferred agents is illustrated by the following:

Procedure

40 Into a solution of 18 parts by weight of para-formaldehyde and 100 parts by weight of strong hydrochloric acid, hydrogen chloride gas was introduced until the solution was saturated. To this mixture, 41 parts by weight of para-isooctyl phenol (para tetramethylbutyl phenol) in benzol solution (50% by weight) were added in the course of one half hour, while stirring well, the temperature increasing from about 15° C. to 50° C. The stirring was continued at 50° C. for an hour after the phenol had been added, and during this time a feeble current of hydrogen chloride was conducted into the solution. The alkyl phenol - formaldehyde - hydrogen chloride condensation product formed remained in solution 45 in the benzol and was separated from the aqueous hydrochloric acid mother liquid. For the second stage of treatment, the separated benzol solution of the condensation product was placed in a beaker, and a dilute liquid ammonia solution in isopropyl alcohol was added to this
